(57) **CLAIM**

The ornamental design for a roof for a vehicle, as shown and described.

DESCRIPTION

FIG. 1 is a front right perspective view of a roof for a vehicle according to the present invention.

FIG. 2 is a rear left perspective view of the roof shown in FIG. 1.

FIG. 3 is a rear right bottom perspective view thereof.

FIG. 4 is a front right bottom perspective view thereof.

FIG. 5 is a front view thereof.

FIG. 6 is a rear view thereof.

FIG. 7 is a left top side view thereof.

FIG. 8 is a right top side view thereof.

FIG. 9 is a top view thereof.

FIG. 10 is a bottom view thereof; and,

FIG. 11 is a top view of the roof shown in FIGS. 1-10, but with the roof mounted on a vehicle, and the rest of the vehicle shown in de-emphasized and half-tone portions so as to illustrate environmental structure. These portions form no part of the claimed design. More particularly, in FIG. 11, the inventive roof is shown within the broken line, and the elements shown outside the broken line form no part of the claimed design, but are instead included to show environmental aspects thereof.
